(57) **CLAIM**

The ornamental design for a pair of car door sill decorative guards, as shown and described.

DESCRIPTION

FIG. 1 is a front and top perspective view of a pair of car door sill decorative guards, showing my new design; FIG. 2 is a rear and bottom perspective view thereof; FIG. 3 is a front elevation view thereof; FIG. 4 is a rear elevation view thereof; FIG. 5 is a left side elevation view thereof; FIG. 6 is a right side elevation view thereof; FIG. 7 is a top plan view thereof; FIG. 8 is a bottom plan view thereof; FIG. 9 is an enlarged view of a portion labeled, 'FIG. 9' in FIG. 1; and,

FIG. 10 is another perspective view thereof, shown in a using position.

The broken lines in the figures illustrate portions of the pair of car door sill decorative guards that form no part of the claimed design. The dash dot dash lines in FIGS. 1 and 9 are for the purpose of depicting the boundary lines of the enlarged view and form no part of the claimed design. The broken lines of a car in FIG. 10 shown in the drawings depict environmental structure that form no part of the claimed design.
